A. A. Gould, of Melrose, Mass.

DES. 2056

Letters Patent No. 82056 Dated May 8, 1876
Design for a Shoe.

The schedule referred to in this Patent and making it of the same.

The following is my statement.

Be it known that G. A. A. Gould of Melrose
in the County of Middlesex and State of Massachusetts, has originated
and produced a new design of ornaments for boots and shoes of
which the following is a full, clear and exact description, reference
being had to the accompanying drawings which are part of this
specification.

My invention is particularly applicable to those boots
and shoes in which the upper part is attached to the instep, such
as such boots or shoes being generally known as Congress Boots, though
my invention is by no means confined to any special kind or pat-
tern of boots or shoes.

In such Congress boots, or in boots or shoes which
lack or button at the side it is desirable to produce an appear-
ance as of a flap covering an opening at the front of the article,
with imitations of straps and buckles representing means for se-
curing the fictitious flap.

The imitation of a flap I produce by stitching in
the vamp as seen at a, the scuff, so formed, giving the appearance
of a flap without the cost of an additional piece of leather to re-

PFS. 2056

2 description, where the straps are formed by small pieces of leather
drawn through imitation buckles & and secured to the waist
with appropriate reference to the season representing the outline
of the flap.

My invention then consists in the imitation of a
flap designed to cover the opening of a front or side, by means
of a tie or cord, with the appendages secured to a imitation strap
referreable.

What I claim as my invention and desire to secure
by letters Patent, is the design for such herein set forth
for articles whereof I have herunto set my hand,
this eighteenth day of March A.D. 1865.
